Louis F. Sayles, Inventor

By Clarence O'Brien.

Attorney

UNITED STATES PATENT OFFICE.

LOUIS FRANCIS SAYLES, OF BROOKFIELD, MISSOURI.

CENTER JOINT AND DOWEL BAR HOLDER.

Application filed August 11, 1926. Serial No. 128,695.

The present invention relates to a center joint and dowel bar holder and has for its principal object to materially assist in the building of concrete roads. It is the custom at the present time in the construction of concrete roads to use a deformed steel joint through the center of the road. The present device is for the purpose of holding this deformed steel center strip absolutely straight and solid and also to hold the dowel bars in place. The dowel bar is a short rod used to tie together the two sides of the concrete slab which is cut in two by the deformed steel center strip.

Another very important object of the invention lies in the provision of a device of this nature which is easy to set in place and remove from the concrete after it has performed its function.

Another very important object of the invention lies in the provision of a device of this nature which is exceedingly simple in its construction, inexpensive to manufacture, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is an elevation of the holder embodying the features of my invention,

Figure 2 is another elevation thereof taken at right angles to that shown in Figure 1.

Referring to the drawing in detail it will be seen that the holder is of a substantially inverted U-shaped formation and includes the legs 5 and the bight portion 6. A shank 7 extends from the center of the bight portion 6 perpendicularly thereto and in opposite direction from the legs 5 and is slightly offset as to the plane in which the bight portion 6 and the legs 5 are disposed. The upper end of this shank 7 terminates in a large head 8. The lower end of the shank 7 merges into an elongated spike 9, much longer than the legs 5 as clearly indicated in the drawing. The terminals of the legs 5 and the spike 9 are preferably sharpened so as to easily pierce the ground. Reinforcing webs 10 are formed integrally with the bight portion 6 and the legs 5 and reinforcing webs 11 are formed

integral with the bight portion 6 and the shank 7. A pin 12 pierces an opening in the head 8. The intermediate portions of the legs 5 are provided with inverted or downwardly disposed hooks 14. Adjacent the lower end of the legs 5 there are formed enlargements 15 which provide stop shoulders 16.

The letter A denotes a common form of steel joint which has a longitudinal center deformed portion indicated by the numeral 17 and provided with openings 18 which register with each other for receiving the vertical spike 9 and an opening 19 for receiving the dowel bars 20 which extend transversely of the deformed steel joint. This steel joint and the dowel bar are well known in this art. It will be seen that the hooks 14 engage the dowel bar and hold it horizontally.

The spike 9 and the lower end of the legs 5 as clearly indicated in Fig. 1, are driven into the ground and rigidly hold the deformed steel joint and dowel bar while the concrete is being poured on either side of the deformed steel joint. There are, of course, several of these holders used. It is the custom to fill in the space between the joint and the side of the form so that considerable strain is imparted to the steel joint.

This steel joint under these circumstances is prevented from toppling over since the concrete in the one side space assists in preventing displacement of the holder because of the enlargement 15 embedded therein. As soon as both the sides of the steel joint have been filled up the holder is removed, the head 8 and pin 12 being provided to allow the removal to be made easy by the use of suitable implements if this is necessary.

In actual practice, however, it is thought unnecessary to use the implements as the head may be grasped by the hand or the pin may be grasped by the hand and the holder pulled out of the relatively soft concrete.

It is thought that the construction, utility, and the advantages of this invention will now be clearly understood by those skilled in this art without a more detailed description thereof. The present embodiment of the invention has been disclosed in detail merely by way of example since in actual practice it attains the features of advantage enumerated as desirable in the statement of the invention in the above description. It will be apparent that numerous changes in the details of construction, in the sizes, pro-

portions of the parts, in the materials, and in the combination and arrangements of parts may be resorted to without departing from the spirit or scope of the invention 5 hereinafter claimed or sacrificing any of its advantages.

Having thus described my invention what I claim as new is:

1. A device of the class described including an inverted U-shaped body to provide a bight and a pair of legs, and a spike projecting from the intermediate bight portion in the same direction with the legs, said spike being disposed out of the plane of the U-shaped body, the upper end of the spike merging into a shank, said shank terminating in a head, reinforcing webs between the shank and the bight portion and between the bight portion and the legs, the legs being provided intermediate their ends with downwardly projecting hooks.
2. A device of the class described including an inverted U-shaped body to provide a bight and a pair of legs, and a spike projecting from the intermediate bight portion in the same direction with the legs, said spike being disposed out of the plane of the U-shaped body, the upper end of the spike merging into a shank, said shank terminating in a head, reinforcing webs between the shank and the bight portion and between the bight portion and the legs, the legs being provided intermediate their ends with down-

wardly projecting hooks, these legs being provided adjacent their ends with enlargements.

3. A device of the class described including an inverted U-shaped body to provide a bight and a pair of legs, and a spike projecting from the intermediate bight portion in the same direction with the legs, said spike being disposed out of the plane of the U-shaped body, each leg being provided intermediate its ends with a downwardly projecting hook.

4. A device of the class described including an inverted U-shaped body to provide a bight and a pair of legs, and a spike projecting from the intermediate bight portion in the same direction with the legs, said spike being disposed out of the plane of the U-shaped body, each leg being provided intermediate its ends with a downwardly projecting hook, each leg being provided adjacent its extremity with an enlargement.

5. A device of the class described including an inverted U-shaped body to provide a bight and a pair of legs, and a spike projecting from the intermediate bight portion in the same direction with the legs, said bight being disposed out of the plane of the U-shaped body, and means on said legs for engaging over a dowel bar.

In testimony whereof I affix my signature.

LOUIS F. SAYLES.
